FURNACE FOR HEATING HYDROCARBON FLUIDS

John Herman Rickerman, River Edge, N. J., assignor to Gasoline Products Company, Inc., Jersey City, N. J., a corporation of Delaware

Application November 17, 1938, Serial No. 240,941.

9 Claims. (Cl. 196—116)

This invention relates to improvements in furnaces for heating hydrocarbon fluids.

A furnace constructed according to my invention may be used for heating fluids such as hydrocarbon fluids to desired temperatures and is especially adapted for heating normally gaseous hydrocarbons to conversion temperatures to convert them into higher boiling normally liquid hydrocarbons containing constituents within the gasoline boiling range.

A furnace embodying the features of my invention includes a radiant heating section for heating hydrocarbon fluids in heater tubes by exposing the heater tubes to direct radiant heat. Burners are provided for supplying hot products of combustion to the furnace. The hydrocarbon fluids are raised to a conversion temperature and then passed through heater tubes in a convection heating section in the furnace for completing the conversion reaction.

The hot products of combustion leave the radiant heating section through a passageway formed by the upper portion of a bridge wall and a vertical wall of the furnace extending above the roof of the radiant heating section. Pre-heater tubes are positioned in this passageway for preheating hydrocarbon fluids before passing them through heater tubes in the radiant heating section while at the same time the hot products of combustion lose some of their heat and have their temperature lowered.

All or a part of the products of combustion leaving the passageway containing the preheater tubes are then passed over heater tubes in the convection heating section for supplying heat to the hydrocarbon fluids in the heater tubes to effect the desired extent of conversion. Means are provided for removing part of the combustion gases to control the heating of the hydrocarbon fluids in the heater tubes in the convection heating section. This means is arranged in the upper portion of the convection heating section and includes a by-pass for by-passing some of the hot products of combustion leaving the radiant heating section and passing over the bridge wall. The by-pass is in alignment with the passage over the bridge wall so that hot products of combustion to be removed may directly pass through the by-pass outlet in substantially a straight line flow. In this way the overheating of the hydrocarbon fluids in the convection heater tubes is prevented. After passing over the convection heater tubes, the products of combustion are passed to a stack.

My invention also includes a method of heating hydrocarbon fluids which includes preheating hy-

drocyan fluids by using all the hot products of combustion leaving the radiant section and controlling the heating of the hydrocarbon fluids in the convection heating section by controlling the volume of combustion gases passing to the convection heating section from the radiant heating section.

In the drawing there is diagrammatically shown a transverse vertical cross section of a furnace embodying my invention.

Referring now to the drawing, the reference character 10 designates a box type or rectangular furnace provided with a radiant heating section 11 and a convection heating section 12 separated from the radiant heating section by a hollow bridge wall 14. The bridge wall extends above the roof of the radiant heating section 11 and forms one side of a passageway 16 through which the hot products of combustion leave the radiant heating section as will be hereinafter more fully described.

The radiant heating section is provided with heater tubes along its boundary surfaces. Roof tubes 20 and 22, wall tubes 24, floor tubes 26 and bridge wall tubes 28 are arranged longitudinally of the radiant heating section along the respective boundary surfaces thereof. In some instances certain of these banks of heater tubes may be omitted if desired. Suitable return bends are provided. Hydrocarbon fluids to be heated to conversion temperatures are passed through inlets 30 and then through banks of preheating tubes 32 and 34, the hydrocarbon fluids passing through each bank of tubes in parallel flow. The preheating tubes 32 and 34 are arranged longitudinally of the furnace. The preheating tubes 32 and 34 are arranged in the passageway 16 adjacent the upper portion of the bridge wall through which all the hot products of combustion leave the radiant heating section 11. If desired, the hydrocarbon fluids may be passed through the preheating section in a single stream instead of plural streams.

After being preheated, the hydrocarbon fluids are passed through the heater tubes in the radiant heating section in plural streams as will be hereinafter described in more detail. The hydrocarbon fluids after being heated in the radiant heating section pass in separate streams through banks of tubes 38, 40, 42 and 44 in the convection heating section 12 and leave the tubes through outlets 46 and 48 to other apparatus for the separation of desired constituents.

Suitable burners 50 are preferably mounted in the walls of the radiant heating section and pro-

vide means for burning fuel such as a hydrocarbon gas for supplying radiant heat for the radiant heating section. The burners are preferably arranged in opposite walls of the radiant section and the burners in one wall may be out of alignment with the burners in the opposite wall so that the burning fuel streams from opposite walls are slightly offset with respect to each other and do not collide in the centers of the radiant heating section. Other arrangements of burners may be used.

The roof 52 of the radiant heating section 11 is lower than the top portion 54 of the bridge wall 14. A vertical wall 56 extends upwardly from the end portion of roof 52 nearest the bridge wall 14 to a point above the top portion 54 of the bridge wall. The vertical wall 56 is spaced from the bridge wall 14 and is substantially parallel thereto to provide the passageway 16 above referred to which conveys the hot products of combustion away from the radiant heating section 11.

The furnace further includes a roof 62 positioned above the bridge wall 14 and convection heating section 12. This roof 62 is spaced from the upper portion 54 of the bridge wall 14 and provides a passageway 64 which forms a continuation of the passageway 16 for conducting hot products of combustion from the radiant heating section and preheating section. The hot products of combustion in passing over the preheater tubes 32 and 34 in the passageway 16 lose some of their heat, and all or a part of the combustion gases are then passed over the convection heater tubes 38, 40, 42 and 44 for heating the hydrocarbon fluids in the convection heater tubes. After passing over the convection heater tubes, the waste gases are passed through flue 65 for passage to a stack (not shown).

When the hot products of combustion after having passed over the preheating tubes 32 and 34 are at too high a temperature, the hydrocarbon fluids in the convection heater tubes or soaking section might be overheated and therefore it is desirable that a part of the combustion gases be removed. For this purpose a by-pass 66 is provided in the upper portion of the convection section 12 above the convection heater tubes. The by-pass 66 has a damper 68 for controlling the volume of combustion gases to be passed to the stack without passing over the convection heater tubes. It will be seen that the by-pass 66 is in alignment with the horizontal portion 64 of the passageway 16 leading from the radiant heating section and in this way the hot products of combustion are easily removed from the furnace in a straight line flow and the amount of combustion gases to be by-passed is easily controlled. The by-pass 66 and damper 68 provide means for controlling the amount of hot products of combustion to be passed through the convection heating section and thereby control the heating of the hydrocarbon fluids passing through heater tubes in the convection heating section. Due to the arrangement of the by-pass 66, overheating of the hydrocarbon fluids in the convection heater tubes in the convection heating section 12 is prevented. Also, by having a controlled lower temperature in the convection heating section, I am enabled to use cheaper refractory material therein.

The roof 52 of the radiant section 11 is provided with a downwardly directed, curved deflecting member 72 extending longitudinally of the furnace for deflecting the hot products of

combustion toward the passageway 16 in which the preheater tubes 32 and 34 are arranged. This deflecting member 72 prevents short circuiting of the hot products of combustion through a portion only of the preheating section 16 and in this way prevents overheating of certain of the preheating tubes 32 and 34.

The flow of hydrocarbon fluids through the furnace, as shown in the drawing, will now be described but it is to be understood that other flows may be used. Hydrocarbon fluids to be heated to conversion temperatures are passed through inlets 30 and pass through the preheating tubes 32 and 34 so that each stream passes in parallel flow through the banks of preheater tubes and becomes preheated. These preheater tubes are positioned in the passageway 16 located between the upper portion of the bridge wall 14 and the vertical wall 56 of the furnace and are heated by the hot products of combustion as they leave the radiant heating section 11. All of the hot products of combustion from the radiant heating section pass through the passageway 16 and over the preheating tubes 32 and 34.

One of the streams of preheated hydrocarbon fluids passing through the bank 34 of the preheater tubes is passed through line 74, through bridge wall tubes 28, through line 76 and roof tubes 20 and leaves the radiant heating section through line 78. The other stream passing through the bank 32 of the preheater tubes is passed through line 82, through the floor tubes 26, through line 84 and then through wall tubes 24 and roof tubes 22 and is then merged with the previously described stream passing through line 78 from the radiant heating section. The heater tubes in the radiant heating section are exposed to direct radiant heat and during their passage through these tubes in the radiant heating section, the hydrocarbon fluids are raised to a conversion temperature.

The single stream of hydrocarbon fluids passing through line 78 is substantially at a conversion temperature and is then subdivided into a plurality of streams and the separate streams are passed through the banks of tubes 38, 40, 42 and 44 in the convection heating section which functions as a soaking section. The hydrocarbon fluids are passed through the convection heating tubes in four streams and may be later merged and leave the convection heating section as a double stream through outlets 46 and 48. If desired the hydrocarbon fluids may be passed through the furnace in a single-stream. The hot products of combustion pass over the preheater tubes in the preheating section 16 and then pass through the passageway 64 above the bridge wall 14.

It is important to control the heating of the hydrocarbon fluids passing through the convection heating tubes in the convection section 12 to prevent overheating of the hydrocarbon fluids and formation and deposition of coke in the convection heater tubes when the hot products of combustion leaving the radiant heating section 11 are at too high a temperature for heating the fluids in the convection heating section, the damper 68 in the by-pass 66 is opened to permit by-passing of some of the hot products of combustion before they contact tubes 38, 40, 42 and 44 in the convection heating section 12. The by-pass 66 forms a continuation of the horizontal portion 64 of the passageway 16 so that the hot products of combustion are easily removed from the furnace in a substantially straight line 75

and the heating of the fluids in the convection heating section is easily and accurately controlled.

In some instances it may be desirable to mix the streams of fluid passing through banks of tubes 38, 40, 42 and 44 in the convection section 12 in order to insure uniform heating of the streams. Lines 80 and 82 interconnect the tube banks 38 and 40 and lines 84 and 86 interconnect the tube banks 42 and 44. In this way possible uneven heating of the several streams in the convection section 12 may be obviated. For example, if the stream in tube bank 38 is not heated as much as the stream in tube bank 40, the interconnecting line 80 will allow the two streams to mix and so come to about an equal temperature and the streams start from this point on an equal basis. Line 88 may be provided to allow mixing of streams in tube banks 40 and 42 to obviate any possible uneven heating. Additional interconnecting lines may be used, or, if desired, the interconnecting lines 80, 82, 84, 86 and 88 may be omitted.

While I have shown one form of a furnace and a flow of hydrocarbon fluids therethrough it is to be understood that these are by way of example only and modifications and changes may be made without departing from the spirit of my invention.

30 I claim:

1. A furnace adapted for heating hydrocarbon fluids which includes a radiant heating section and a convection heating section separated by a bridge wall disposed to extend above the roof of said radiant heating section, heater tubes arranged along at least one boundary surface of said radiant heating section, heater tubes in said convection heating section and communicating with and adapted to receive heated hydrocarbon fluids from said heater tubes in said radiant heating section, means for supplying hot combustion products to said radiant heating section for heating the hydrocarbon fluids in the heater tubes therein, a wall extending upwardly from the roof of said radiant heating section and spaced from the upper portion of said bridge wall to form a passageway therewith for conducting hot products of combustion from said radiant heating section to said convection heating section, preheater tubes in said passageway adapted to be heated by the hot products of combustion passing through said passageway to preheat hydrocarbon fluids before passing them through said heater tubes in said radiant heating section, a second passageway extending over said bridge wall and communicating with said first mentioned passageway for conducting products of combustion to said convection heating section, and a by-pass arranged at the upper portion of said convection heating section above the heater tubes therein and in alinement with the second passageway which extends over said bridge wall whereby part of the hot products of combustion leaving said radiant heating section and after passing over said preheater tubes may be removed from said furnace in a substantially straight line without passing over the heater tubes in said convection heating section to prevent overheating of the hydrocarbon fluids passing through the heater tubes in said convection heating section.
2. A furnace adapted for heating hydrocarbon fluids which includes a radiant heating section and a convection heating section separated by a bridge wall disposed to extend above the roof of said radiant heating section, heater tubes ar-

bridge wall disposed to extend above the roof of said radiant heating section, heater tubes arranged along boundary surfaces of said radiant heating section, heater tubes in said convection heating section and in communication with and adapted to receive heated hydrocarbon fluids from said heater tubes in said radiant heating section, means for supplying hot combustion products to said radiant section for heating the tubes therein by direct radiant heat, a wall extending upwardly from the roof of said radiant section and spaced from the upper portion of said bridge wall to form a passageway therewith for conducting substantially all the hot products of combustion away from said radiant heating section, preheater tubes in said passageway for preheating hydrocarbon fluids before passing them through said heater tubes in said radiant heating section, said passageway extending over said bridge wall for conducting products of combustion to said convection heating section, the roof of said radiant heating section adjacent said passageway being provided with deflecting means to direct hot products of combustion into said passageway and prevent short circuiting of the hot products of combustion through only a portion of said passageway, and a by-pass arranged at the upper portion of said convection heating section above the heater tubes therein and in alinement with the portion of the passageway which extends over said bridge wall whereby part of the hot products of combustion leaving said radiant heating section and after passing over said preheater tubes may be removed from said furnace without passing over the heater tubes in said convection heating section to prevent overheating of the hydrocarbon fluids passing through said convection heating section.

3. A furnace adapted for heating hydrocarbon fluids which includes a radiant heating section and a convection heating section separated by a bridge wall disposed to extend above the roof of said radiant heating section, heater tubes arranged along a boundary surface of said radiant heating section, heater tubes in said convection heating section and in communication with said heater tubes in said radiant heating section, means for supplying hot combustion products to said radiant heating section for heating the heater tubes therein by direct radiant heat, a wall extending upwardly from the roof of said radiant heating section and spaced from the upper portion of said bridge wall to form a passageway for conducting hot products of combustion from said radiant heating section to said convection heating section, preheater tubes in said passageway for preheating hydrocarbon fluids before passing them through said heater tubes in said radiant heating section, said passageway extending over said bridge wall, and means including a by-pass arranged at the upper portion of said convection heating section above the heater tubes therein whereby part of the hot products of combustion leaving said radiant heating section and after passing over said preheater tubes may be removed from said furnace without passing over the heater tubes in said convection heating section to prevent overheating of the hydrocarbon fluids passing through said convection heating section.

4. A furnace adapted for heating hydrocarbon fluids which includes a radiant heating section and a convection heating section separated by a bridge wall disposed to extend above the roof of said radiant heating section, heater tubes ar-

ranged along a boundary surface of said radiant heating section, heater tubes in said convection heating section and in communication with said heater tubes in said radiant heating section, 5 means for supplying hot combustion products to said radiant heating section, a wall extending upwardly from the roof of said radiant section and spaced from the upper portion of said bridge wall to form a passageway for conducting all the hot 10 products of combustion away from said radiant heating section, a preheating section including preheater tubes in said passageway for preheating hydrocarbon fluids before passing them through said heater tubes in said radiant heating section, said passageway extending over said bridge wall and being in communication with said convection section, and means arranged at the upper portion of said convection heating section above the heater tubes therein whereby only a 15 part of the hot products of combustion leaving said preheater section is passed over the heater tubes in said convection heating section to control the heating of the hydrocarbon fluids passing through said convection heating section.

25 5. A furnace adapted for heating hydrocarbon fluids which includes a radiant heating section and a convection heating section separated by a bridge wall, heater tubes arranged along boundary surfaces of said radiant heating section, heater tubes in said convection heating section and in communication with and adapted to receive heated hydrocarbon fluids from said heater tubes in said radiant heating section, means for supplying hot products of combustion to said 30 radiant heating section for heating the tubes therein by direct radiant heat, a wall spaced from said bridge wall to form a passageway therewith for conducting substantially all hot products of combustion away from said radiant heating section and directing them toward said convection heating section, preheater tubes in said passageway for preheating hydrocarbon fluids before passing them through said heater tubes in said radiant heating section, and a by-pass arranged 35 adjacent said convection heating section whereby part of the hot products of combustion after leaving said radiant heating section and after passing over said preheater tubes may be removed from said furnace without passing over the heater tubes in said convection heating section to prevent overheating of the hydrocarbon fluids passing through the heater tubes in said convection heating section.

40 6. A furnace adapted for heating hydrocarbon fluids which includes a radiant heating section and a convection heating section separated by a bridge wall, heater tubes arranged along boundary surfaces of said radiant heating section, heater tubes in said convection heating section and in communication with and adapted to receive heated hydrocarbon fluids from said heater tubes in said radiant heating section, means for supplying hot products of combustion to said 45 radiant heating section for heating the tubes therein by direct radiant heat, a wall spaced from said bridge wall to form a passageway therewith for conducting substantially all hot products of combustion away from said radiant heating section and directing them toward said convection heating section, preheater tubes in said passageway for preheating hydrocarbon fluids before passing them through said heater tubes in said radiant heating section, said passageway formed by the upper portion of the bridge wall and a wall of the furnace, the preheater tubes being swept by all the hot products of combustion leaving said radiant heating section for preheating the hydrocarbon fluid before it is passed to said radiant heating section, and means for controlling the further heating of the hydrocarbon fluid passing through the heater tubes in said convection heating section, said means including a by-pass whereby a part of the hot products of combustion after passing over said preheater tubes are removed from the furnace and the rest of the products of combustion are passed over the heater tubes in said convection heating section.

50 70 7. An apparatus as defined in claim 7 wherein the heater tubes in said convection section are arranged to subdivide the heated fluid into a plurality of separate streams and which further includes means whereby the separate streams may be mixed at least at one point during their passage through said convection section to obviate uneven heating of the separate streams.

ing over said bridge wall, and a by-pass arranged at the upper portion of said convection heating section above the heater tubes therein and in alignment with the portion of the passageway which extends over said bridge wall whereby the further heating of the hydrocarbon fluids in the heater tubes in the convection heating section is controlled by removing part of the products of combustion leaving said radiant section after passing over said preheater tubes and passing the rest of the products of combustion over the heater tubes in said convection heating section.

7. A furnace adapted for heating fluids which includes a radiant heating section and a convection heating section separated by a bridge wall, 15 heater tubes arranged along boundary surfaces of said radiant heating section, heater tubes in said convection heating section and in communication with and adapted to receive heated fluids from said heater tubes in said radiant heating section, means for supplying hot products of combustion to said radiant heating section for heating the tubes therein by direct radiant heat, means providing a passageway for removing substantially all of the hot products of combustion 20 leaving said radiant heating section and directing them toward said convection heating section, preheater tubes in said passageway for absorbing heat from the products of combustion passing through said passageway to preheat fluids before 25 passing them through said heater tubes in said radiant heating section, and a by-pass arranged adjacent said convection heating section whereby part of the products of combustion after passing over said preheater tubes may be removed 30 from said furnace before passing over the heater tubes in said convection section.

8. In a furnace having radiant and convection heating sections separated by a bridge wall disposed to extend above the roof of said radiant heating section, the heating sections being provided with heater tubes for conducting hydrocarbon fluid to be heated through the furnace and means for supplying hot products of combustion to said radiant heating section for heating the heater tubes therein by direct radiant heat, the improvement which includes a preheating section having preheater tubes positioned in a passageway formed by the upper portion of the bridge wall and a wall of the furnace, the preheater tubes being swept by all the hot products of combustion leaving said radiant heating section for preheating the hydrocarbon fluid before it is passed to said radiant heating section, and means for controlling the further heating of the hydrocarbon fluid passing through the heater tubes in said convection heating section, said means including a by-pass whereby a part of the hot products of combustion after passing over said preheater tubes are removed from the furnace and the rest of the products of combustion are passed over the heater tubes in said convection heating section.

9. An apparatus as defined in claim 7 wherein the heater tubes in said convection section are arranged to subdivide the heated fluid into a plurality of separate streams and which further includes means whereby the separate streams may be mixed at least at one point during their passage through said convection section to obviate uneven heating of the separate streams.
